(57) **CLAIM**

The ornamental design for eyewear with removable insert, as shown and described.

DESCRIPTION

FIG. 1 is a front perspective view of the eyewear with removable insert showing my design.

FIG. 2 is rear perspective view thereof.

FIG. 3 is a outside left elevation view of the eyewear with removable insert, the right outside being a mirror image thereof.

FIG. 4 is a front elevation view of the eyewear with removable insert.

FIG. 5 is a rear elevation view of the eyewear with removable insert.

FIG. 6 is a top plan view of the eyewear with removable insert.

FIG. 7 is a bottom plan view of the eyewear with removable insert.

FIG. 8 is an exploded partial front perspective view of the eyewear with removable insert.

FIG. 9 is an exploded partial rear perspective view of the eyewear with removable insert; and,

FIG. 10 is an exploded left elevation view of the eyewear with removable insert, the right side being a mirror image thereof.
